UNITED STATES PATENT OFFICE.

WILLIAM E. BEAKES, OF NEW ORLEANS, LOUISIANA, ASSIGNOR TO UNITED FRUIT COMPANY, OF BOSTON, MASSACHUSETTS, A CORPORATION OF NEW JERSEY.

PROCESS AND APPARATUS FOR WIRELESS TELEGRAPHY AND TELEPHONY.

Application filed July 1, 1918. Serial No. 242,693.

To all whom it may concern:

Be it known that I, WILLIAM E. BEAKES, a citizen of the United States, residing at New Orleans, parish of Orleans, State of Louisiana, have invented certain new and useful Improvements in Processes and Apparatus for Wireless Telegraphy and Telephony, of which the following is a specification.

My invention relates to improvements in wireless telegraphy and telephony, and especially to the so-called aerial or antenna. It is well known that in order to receive signals of a given wave length the antenna of the receiving station must be "tuned" or adjusted so that its natural wave length corresponds more or less closely with the wave length of the incoming signals, and likewise, since the wave length of the outgoing signals at a transmitting station depends upon the natural period of the antenna, the antenna is made adjustable in such a manner as to vary its natural period in accordance with the wave length which it is desired to transmit.

Heretofore it has been common practice to "tune" or adjust the antenna so as to give it a desired natural period or wave length by varying the factors of inductance or capacity. The object of my invention is to avoid the necessity of using a large inductance or capacity in the antenna for the purpose of adjusting it to desired wave lengths, and thereby to increase the efficiency of the antenna both when the apparatus is used in a transmitting system and when it is used in a receiving system. In accordance with my invention, the adjustment of the antenna to a given wave length is effected in part or in whole by increasing or decreasing its op-

erative length, that is to say, the length of its conducting parts. By this means I am enabled to do away with the use of large inductance or capacity in the antenna circuit. I have found that by adjusting the antenna to the desired wave length in this manner a much stronger signal is received or transmitted than would be the case if the adjustment were provided for by including in the system the usual large amount of inductance and capacity and varying these factors. I do not, in practicing my invention, necessarily omit from the circuit all inductance and capacity elements, but am enabled to minimize these factors.

A suitable apparatus for carrying out my

invention is illustrated in the accompanying drawing, in which 1 represents a line composed of any non-conducting material, such as silk or hemp, and 2 a line of any good conducting material, such as copper or silver, which acts as a part of the antenna circuit. These two lines are connected together by a joint 3, and are conveniently arranged to pass over a pulley or pulleys 4. The line 2 is attached to a metallic drum, 6 spool or cylinder 5 upon which it may be wound by turning the drum in one direction and from which it is unwound when the drum is turned in the reverse direction. 6 is a drum to which the end of the line 1 is attached so that the line 1 may likewise be wound upon or unwound from this drum, as the drum is turned in one or the other direction. 8 is a motor for rotating these drums in one or the other direction, and 7, 75 7 are insulated couplings connecting the drums to the motor. 10 represents a suitable handle for manually rotating the drums. 9 is a line of conducting material connecting the metal drum 5 with the lead 11 to the receiving instruments, or with the lead 12 to the sending instruments. After passing the sending or receiving instruments, the antenna circuit is, of course, completed by a connection to the ground. By turning the 80 drums 5, 6 in one direction the operative length of the antenna 2 is lengthened, and by turning them in the opposite direction it is shortened; and the operative length of the antenna may thus be conveniently 85 changed in order to adjust it to desired wave frequency, the drums being rotated either by means of the motor 8 or by manipulation of the hand crank 10.

This apparatus may be inserted in any of the well known receiving and transmitting circuits. Any number of lines and drums may be employed, although in the accompanying drawing I have shown only one set of lines as they are sufficient to illustrate the invention. The lines may be suspended from masts or may be embedded in the earth, and they may be in either horizontal, vertical or angular position, depending upon the form of antenna construction desired.

Other forms of apparatus than that illustrated may obviously be employed to carry out my invention which, broadly, consists in the method of adjusting, or aiding the ad-

justment of, the antenna to a desired wave length by varying its length, and in apparatus as described in the accompanying claims. By the term "aerial portion" of the 5 antenna as used in the appended claims, I mean that portion of the antenna circuit which is exposed to incoming electro-magnetic waves or radiations, and whose function it is to collect energy from them when 10 the apparatus is used as a receiver for wireless signals, and which, when the apparatus is used as a transmitter for wireless signals, radiates electro-magnetic waves to be received at a distant station.

15 What I claim, and desire to secure by Letters Patent is:—

1. In an apparatus of the character described, an antenna, and, attached thereto, a cord of non-conducting material, drums 20 for winding and unwinding portions of said

antenna and of said cord, and means for rotating said drums.

2. In an apparatus of the character described, an antenna, and, attached thereto, a cord of non-conducting material, drums 25 for winding and unwinding portions of said antenna and of said cord, and means for rotating said drums, including a motor.

3. The method of tuning an antenna which includes adjusting it to desired wave 30 length by physically shortening and lengthening its aerial portion by winding and unwinding the same on a rotatable member.

In testimony whereof, I have hereunto set my name in the presence of two witnesses this 25th day of June, 1918.

WILLIAM E. BEAKES.
